UNITED STATES PATENT OFFICE.

CHARLES A. LINDSTRÖM, OF ALLEGHENY, PENNSYLVANIA, ASSIGNOR TO
PRESSED STEEL CAR COMPANY, OF PITTSBURG, PENNSYLVANIA, A
CORPORATION OF NEW JERSEY.

CAR-DOOR MECHANISM.

SPECIFICATION forming part of Letters Patent No. 758,456, dated April 26, 1904.

Application filed July 22, 1903. Serial No. 166,538. (No model.)

To all whom it may concern:

Be it known that I, CHARLES A. LINDSTRÖM, of Allegheny, Allegheny county, Pennsylvania, have invented a new and useful Car-Door Mechanism, of which the following is a full, clear, and exact description, reference being had to the accompanying drawings, forming part of this specification, in which—

Figure 1 shows in end elevation a hopper-car provided with my improvement, the body of the car being indicated in dotted outline; and Fig. 2 is a vertical longitudinal section on the line II II of Fig. 1.

In the drawings, 2 2 represent the side sills. 3 is the bolster, and 4 4 are doors at the bottom of the car hinged at pivots 5 5. My invention relates to novel mechanism for operating these doors.

6 is the operating-shaft, which extends across the car and has, preferably at both ends, squared portions for the application of a handle or hand-wheel, by which it may be rotated. On this shaft are a pinion 7 and a ratchet-wheel 8, provided with a locking-pawl 9. The pinion 7 is in gear with a gear-wheel 10 at the middle portion of a shaft 11, which also extends across the car, the shafts 6 and 11 being journaled in bearings 12 12 on the side sills 2 and the center sill 13. The door-operating chains 14 are attached to the shaft 11, near the ends thereof, and pass thence over guide-pulleys 15 to the doors, to which they are connected at 16. The pulleys 15 are set on shafts 17, which extend at an inclination between bearings 18, which are respectively on the inner sides of the sills 2, and on brackets 19, which project from the side of the hopper. The shaft and pulley being thus inclined, the chain passes directly from the pulley to the car-door, and there is no tendency for the chain in operation to leave the groove of the pulley.

The locking-pawl 9 is operated by a crank-shaft 20, which extends across the car and is connected to the pawl by a link 21. The shaft 20 is preferably provided with an operating-handle 20' at each end, so that it may be operated at either side of the car to lift the pawl,

and thus to free the shafts 6 and 11 and permit the doors to drop. The parts are so placed that when the pawl 9 is in locking engagement the pivotal connection of the link 21 with its crank will be past the dead-center, so that any tendency of the pawl 9 to rise will only press the handle 20' against the beam 22 or other part of the car-frame, by which it is stopped. This prevents effectually the disengagement of the pawl, which can only be disengaged by upward motion of the handle 20'.

The operation is as follows: To raise the door, the operator raises the pawl 9 by operating the crank-shaft 20 and then rotates the chain-shaft 6, which through the pinion 8 and the larger wheel 10 rotates the chain-shaft 14 at a less speed and winds the chains on this shaft until the doors are closed. As the power is applied to the chain-shaft 11 at its middle portion and transmitted to the chains near the ends of the shaft, the twisting moment on the shaft is reduced to a minimum. A like effect is had upon the shaft 6 by locating the holding-ratchet 7 and pawl 9 at its middle portion. This is a matter of importance, as it enhances the ease of operation of the parts and renders them more durable.

Within the scope of my invention as defined in the claims the parts may be modified in construction, since

What I claim is—

1. Car-door mechanism comprising a chain-shaft extending transversely of the car, chains attached thereto and passing over inclined guide-pulleys to the door, and intermediately-located, power-transmitting gearing on said chain-shaft; substantially as described.

2. Car-door mechanism comprising a transverse chain-shaft, chains connecting the door with the ends of said shaft, a secondary power-shaft having an intermediate retaining-ratchet, and a pinion on said secondary shaft for transmitting power to the middle of said chain-shaft; substantially as described.

3. Car-door mechanism comprising a transverse chain-shaft, chains connecting said door to the ends of said shaft, a gear near the center of said shaft, a secondary power-shaft, an

intermediate retaining-ratchet and a pinion on said power-shaft, said pinion meshing with said chain-shaft gear; substantially as described.

5. In a car-door mechanism, a power-shaft, an intermediate ratchet on said shaft and a toggle-locked retaining-pawl adapted to engage said ratchet; substantially as described.

5. Car-door mechanism comprising in combination with an operating-shaft, a locking-pawl at the middle portion thereof, and a crank-shaft extending from side to side of the car and connected with the pawl; substantially as described.

6. Car-door mechanism having a locking ratchet and pawl, a crank-shaft for the pawl, a link between the crank and pawl, an operating-handle and a stop, said parts being arranged relatively to each other so that when the pawl is engaged the link shall be at or past its dead-center; substantially as described. 15 20

In testimony whereof I have hereunto set my hand.

CHARLES A. LINDSTRÖM.
